UNITED STATES PATENT OFFICE.

ANTHONY GIARDINO, OF BROCKTON, MASSACHUSETTS.

CLASP.

1,344,500.

Specification of Letters Patent. Patented June 22, 1920.

Application filed September 16, 1916. Serial No. 120,491.

To all whom it may concern:

Be it known that I, ANTHONY GIARDINO, a citizen of the United States, residing at Brockton, in the county of Plymouth and State of Massachusetts, have invented certain useful Improvements in Clasps, of which the following is a specification, reference being had therein to the accompanying drawing.

10 The invention relates to tag holders and more particularly to the class of combined tag clasps and hangers therefor.

The primary object of the invention is the provision of a combined device of this character wherein a tag containing stock indicia for the marking of merchandise will be securely held and hung upon the merchandise without possibility of the accidental loss of the tag and also will hold the same 20 so that it can be readily inspected.

Another object of the invention is the provision of a device of this character wherein the tag when supported thereby can be readily reversed or turned for the inspection of 25 either side thereof when the same is hung upon merchandise thereby enabling convenient identification of such merchandise and the inspection of the tag thereon.

A further object of the invention is the 30 provision of a device of this character wherein the tag can be engaged with the merchandise with despatch and will be firmly fastened thereto so as to avoid the separation of said tag and merchandise.

35 A still further object of the invention is the provision of a device of this character which possesses simplicity in construction and effectiveness in its purpose, ready and convenient application of the tag to the merchandise and the handling thereof when hung thereon and also which is inexpensive in manufacture.

With these and other objects in view the invention consists in the features of construction, combination of elements, and arrangement of parts as will be hereinafter 45 fully described, illustrated in the accompanying drawings, and pointed out in the claim hereunto appended.

50 In the accompanying drawings:

Figure 1 is a fragmentary perspective view of a shoe showing a tag supported by the device constructed in accordance with the invention applied.

55 Fig. 2 is a vertical longitudinal sectional view through the device.

Fig. 3 is a perspective view of the hanger for the clasp.

Fig. 4 is a perspective view of a modified form of combined hanger and clasp. 60

Fig. 5 is a fragmentary longitudinal sectional view therethrough.

Similar reference characters indicate corresponding parts throughout the several views in the drawings. 65

Referring to the drawings in detail, A designates generally a tag which is of the ordinary well-known construction having suitable marking or indicia thereon for identification purposes in the tagging of merchandise, for example a shoe B, the tag A being detachably connected or hung upon the latter by the use of the combined hanger and clasp hereinafter described. 70

The combined hanger and clasp comprises 75 the pivotally connected jaw members 10 which constitute the clasp proper which are closed through the medium of a coil tension spring 11 supported upon the pivot 12 connecting the jaw members 10 together and 80 one of these jaw members carries a lug or stud 13, while the other jaw member is formed with an opening 14 receiving the lug or stud 13 when both jaw members are closed. The lug or stud 13 on one jaw member 85 engages in the reinforced eyelet 15 formed in the tag A so that the latter can be detachably held in the clasp which has its jaw members extended to form levers 16 for permitting a convenient opening of the 90 jaw members to engage the tag A therein or disengage it from the clasp.

Loosely engaged in suitable openings in the lever 16 of the jaw members are the hook ends 17 of an inverted U-shaped resilient yoke 18 which is preferably formed from a single length of wire bent medially thereof to form a coil eye 19 centrally of said yoke and in which is fastened a swivel pin 20 for the connection of an attaching pin 100 member therewith hereinafter described. 95

The attaching pin member comprises a substantially triangular shape frame 21 formed from a single length of resilient wire bent on itself to provide a prong or tine 22 105 at one end portion and a keeper in the form of an open eye of hook 23 in which is detachably engaged the prong or tine 22 for the closing of the frame 21. The frame 21 at one point thereof is bent to form a coiled 110 eye 24 in which is received a swiveled pin 20 so that in this manner the frame 21 is

loosely connected to the yoke 18 and by reason thereof the tag A can be readily turned or reversed when fastened in the clasp so that either side thereof can be inspected 5 for identification purposes in the handling of the merchandise on which the tag is hung.

In Fig. 4 is shown a slight modification of the combined hanger or clasp wherein 10 the jaw members 25 are formed with substantially segmental shaped ends 25 which serve as guards for the tag when fastened within the clasp while the lever ends 26 of the jaw members 25 has swiveled therein the 15 right angular crank extension 27 of a hanger link 28 which is formed from a single length of wire and is provided at the opposite end with a short right angled swivel extension 29 on which is swiveled the coiled eye 20 30 of the hanger frame 31 which is identical to the construction of the frame 21 with the exception that the coiled eye 30 is at right angles to the plane of the frame 31, which

is adapted for detachable engagement in the pull loop or back-strap 32 of the shoe B for 25 the hanging and fastening of the tag thereon. Likewise the frame 21 is engageable with the pull loop or back-strap 32 of the shoe B as shown in Fig. 1 of the drawings.

From the foregoing it is thought that the 30 construction and manner of use of the clasp will be clearly understood and therefore a more extended explanation has been omitted.

What is claimed is:

In a device as described, in combination, 35 a crank, a clasp having a pair of jaws, lateral ears on said jaws, pivots adapted to connect said lateral ears together, a head formed upon one end of one arm of said 40 crank, and a spring adapted to separate said jaws so that one jaw will engage the head on said arm and the other jaw will engage the other arm of said crank.

In testimony whereof I affix my signature. 45

ANTHONY GIARDINO.
